UNITED STATES PATENT OFFICE

VERN M. OSBORN, OF LOS ANGELES, CALIFORNIA

TRAFFIC SIGNAL DEVICE

Application filed November 24, 1928. Serial No. 321,576.

This invention relates to traffic signal devices.

The general object of the invention is to provide an improved traffic signal device 5 wherein the signalling mechanism is disposed on a low platform which may be portable.

A further object of the invention is to provide a traffic direction indicator wherein a portable stand is provided for a directing officer and wherein the stand is surrounded by 10 a rotatable direction signalling device.

A further object of the invention is to provide a traffic signal which is adapted to be operated through suitable power operated 15 mechanism.

Other objects of the invention will be apparent from the following description taken in connection with the accompanying drawings wherein:

20 Fig. 1 is a perspective view showing my portable manually operated device.

Fig. 2 is a central longitudinal section through the device shown in Fig. 1.

Fig. 3 is a top plan view of the device partly in section.

Fig. 4 is a section taken on line 4—4 of Fig. 2.

Fig. 5 is a side elevation of a modified form of my invention.

25 Fig. 6 is a longitudinal section through the modified form of my device showing parts in elevation.

Fig. 7 is a top plan view of the modification with parts in section.

Fig. 8 is a wiring diagram of the modified form.

Fig. 9 is a section through a further modification of my invention.

Fig. 10 is a section on line 10—10 of Fig. 9, and

Fig. 11 is a wiring diagram of the invention shown in Fig. 9.

Referring to the drawings by reference characters I have indicated my traffic signal generally at 10. As shown this signal comprises a body including a bottom portion 11 having a cylindrical member 12 secured thereon. The cylindrical member is surmounted by a top 14 which has a cover 15 thereon.

The top 14 is circular and is rabbeted about the periphery as at 16. At intervals about this periphery I provide rollers 17 mounted on horizontal axles 18. Upon these rollers I fit a flange 19 of a signal member indicated 55 generally at 20.

The signal member 20 may be of rectangular or other shape and includes sides 21. These sides are apertured as at 22 and 23 and back of these apertures I place panels 24. 60 These panels 24 have the words "Go" and "Stop" or other suitable indicia thereon. The lower portion of the signal member 20 is provided with suitable spaced rollers 25 which bear against the wall of the member 12. 65

Secured to two adjacent sides I show an arcuate rack 26 which is engaged by a gear 26^a mounted on one end of a shaft 27 which passes through collars 28 on the member 12. The other end of the shaft is supported in 70 bearings 29 and 30. Between these bearings I show a pinion 31 which is adapted to be engaged by a gear 32 on a shaft 33. The shaft 33 also has a pinion 34 secured thereon which is engaged on each side by racks 35 and 36. 75 The rack 35 has a pedal 37 thereon while the rack 36 has a pedal 38 thereon. The racks are so disposed that when one pedal is up the other will be down.

In operating my invention the officer will 80 place the signal in the proper position and while standing on the cover 15 will put his foot on the pedal which projects upwardly and will push this pedal down. This will cause the signal member 20 to rotate through 85 90° thereby causing the "Stop" and "Go" signals to move. As the pedal is depressed the other pedal rises where it is available to change the signals when desired.

In Figs. 5 to 8 inclusive I have shown a 90 modified form of my invention. In this modification the bottom portion 11a, the cylindrical portion 12a, the top 14a, and the cover 15a, are shown as similar in all respects to the parts 11, 12, 14 and 15 previously described, with the exception that the cylinder 12a is of less diameter relative to the top 14a. 95 Rollers 17a are engaged by a flange 40. A flange 41 supports rollers 25a which engage the wall of the member 12a. These flanges 100

are arranged on the sides of signal member 42 which has apertures 43 therein. Panels 44 having suitable indicia thereon are fitted in the apertures. The indicia on these panels is preferably translucent.

The flange 41 is shown as provided with a rack 45 which is engaged by a pinion 47 mounted on a shaft 48. The shaft 48 is mounted in a bearing 49 and has thereon a worm wheel 50 which is adapted to be driven by a worm 51, mounted on the armature shaft of a motor 52. The motor 52 is of the reversible type and is shown as supported by brackets 53 depending from the top 14a.

From the foregoing description it will be apparent that when the motor is operated the signal member 42 will be turned in a direction depending on the direction of rotation of the motor.

22. Mounted on the cylindrical portion 12a I have shown lamps 55 which serve to illuminate the panels 44 and a lamp 56 mounted on a standard 57 is preferably provided for illuminating the platform and the office thereon.

23. Mounted on an insulated base 58 which is secured to the member 40 I provide two segmental sets of double-faced tracks 59 and 60. One of the tracks projects at one end beyond the other and the other track projects at the opposite end as clearly shown in Figs. 7 and 8.

The track 59 is adapted to bridge contacts 61 and 62 and the track 60 is adapted to bridge contacts 63 and 64.

24. The contact 61 is connected by a wire 65 to one side of the motor 52 and the contact 62 is connected by a wire 66 to a contact 67. The contact 67 and a companion contact 68 are adapted to be bridged by a contact bar 69 mounted on a pivoted switch lever 70. This lever may be actuated in any desired manner but I have shown it as secured to a shaft 71 which is adapted to be rotated by a handle 72 positioned adjacent the standard 57.

25. The contact 68 is connected to one side of a source of electrical energy which is shown as a battery 74 by a wire 75 and a control switch 76. The other side of the battery is connected to one side of each of the forward and reverse windings of the motor 52 by a wire 77.

26. The contact 64 is connected to one side of the motor 52 by a wire 78 and the contact 63 is connected to a contact 79 by a wire 80. The contact 79 and a companion contact 81 are also adapted in one position of the lever 70 to be bridged by the contact bar 69. The contact 81 is connected through the switch 76 to the battery 74 by a wire 82.

27. From the foregoing it will be apparent that when the switch 76 is closed electric current will flow from the battery 74 to the contacts 68 and 81. When the lever 70 is moved to cause the contact bar 69 to bridge the contacts 67 and 68 and the track 59 bridges the con-

tacts 61 and 62 as shown in Fig. 8, the current will flow from the battery through wire 75 to the contact 68, through the contact bar 69 to the contact 67 and thence through the wire 66 to the contact 62. From the contact 62 the current will flow through the track 59 to the contact 61 and then through the wire 65 to one side of the motor 52, actuating the motor and returning to the battery through wire 77.

Upon actuation of the motor the worm 51 will drive the worm wheel 50 which in turn will drive the gear 41 and cause the signal member 42 to revolve until it has moved a sufficient distance to cause the track 59 to pass the contacts 61 and 62, whereupon the circuit to the motor is broken, thereby stopping the motor.

When the signal device 42 has moved a short distance the track 60 moves into position between the contacts 63 and 64 and bridges them but does not complete a circuit until the contacts 79 and 81 are bridged by the contact bar 69. Thus when the track 59 has moved out of engagement with the contacts 61 and 62 and the motor stopped the device is in a position whereby upon the bridging of the contacts 79 and 81 by the contact bar 69 the motor will be actuated to rotate the signal device in the opposite direction.

When the contacts 79 and 81 are bridged by the contact bar 69 the current will flow from the battery through the wire 82 to the contact 81, thence through the contact bar 69 to the contact 79 and through wire 80 to contact 63.

From the contact 63 the current passes through the track 60 to the contact 64 and thence through the wire 78 to one side of the motor 52, actuating the motor to rotate the signal member 40 as previously described but in the opposite direction and returning to the battery through wire 77. The motor continues to move the signal member 42 until the track 60 moves out of engagement with the contacts 63 and 64 as shown in Fig. 8, thereby breaking the circuit to the motor.

The lights 55 and 56 are shown as electrically connected to the battery 74 by wires 84 and 85.

For automatically controlling the actuation of my device I provide a pair of automatic switches indicated at 87 and 88 (Fig. 8). The switch 87 is adapted to control the circuit which is manually controlled by the contacts 67 and 68 and the switch 88 is adapted to control the circuit which is manually controlled by the contacts 79 and 81.

The switch 87 includes an arm 89 made of a thermal responsive metal which is adapted to be heated by an electrical resistance coil 90. One end of the coil 90 is connected by a wire 91 to a contact 92 and the other end of the coil is connected by a wire 93 to a

wire 94 which connects to the battery through a control switch 95.

The switch 88 is similar to the switch 87 and includes a thermal responsive metal arm 96 which is adapted to be heated by an electrical resistance coil 97. One end of the coil 97 is connected by a wire 98 to a contact 99 and the other end of the coil is connected by a wire 100 to the battery wire 94.

10 The contact 92 and a companion contact 101 are adapted to be bridged by the track 60 and the contact 99 and a companion contact 102 are adapted to be bridged by the track 59.

15 When the contacts 92 and 101 are bridged by the track 60 the current will flow from the battery through switch 95 and wires 94 and 93 to the coil 90, through the coil 90 and a wire 91 to the contact 92 thence through the track 60 to the contact 101 and then through a wire 103 to the wire 77 and therethrough to the battery.

20 When the contacts 99 and 102 are bridged by the track 59 the current will flow from the battery through the wires 93 and 100 to the coil 97, through the coil and wire 98 to the contact 99 and thence through the track 59 to the contact 102 from whence it will flow through a wire 104 and return to the battery through the wire 77.

25 The switch 87 includes a pair of contacts 105 and 106 which are adapted to be bridged by a contact bar 108 on the arm 89. The contact 105 is connected by a wire 109 to the battery wire 94 and the contact 106 is connected by a wire 110 to the motor wire 65.

30 The switch 88 includes a pair of contacts 112 and 113 which are adapted to be bridged by a contact bar 114 on the arm 96. The contact 112 is connected by a wire 115 to the battery wire 94 and the contact 113 is connected by a wire 117 to the motor wire 78.

35 When the contacts 105 and 106 are bridged by the contact bar 108 the current will flow from the battery through wires 94 and 109 to the contact 105 and thence through the contact bar 108, contact 106 and wire 110 to the motor wire 65 thereupon actuating the motor in one direction.

40 When the contacts 112 and 113 are bridged by the contact bar 114 the current will flow from the battery through wires 94 and 115 to the contact 112 and thence through the contact bar 114, contact 113 and wire 117 to the motor wire 78 thereupon actuating the motor in the opposite direction.

45 When it is desired to start the automatic switches 87 and 88 the switch arm 70 is moved to a neutral position wherein the contact bar 69 will not bridge either the contacts 67 and 68 or the contacts 79 and 81 and then the switch 95 is closed. If the tracks 59 and 60 are in the position shown in Fig. 8 when the switch 95 is closed the current will flow to the coil 90 of the switch 87 whereupon the

50 coil will be heated and heat the thermal responsive arm 89. As the arm heats it moves towards the contacts 105 and 106 and establishes a circuit from the battery to the motor as previously described, thereby actuating the motor to rotate the signal member 40 and tracks 59 and 60 in one direction. As the track 60 reaches the end of its travel it disengages from the contacts 92 and 101 thereby breaking the circuit to the coil 90 whereupon the arm 89 begins to cool and move the contact bar 108 out of engagement with the contacts 105 and 106 thereby breaking the circuit to the motor.

55 As the signal device 42 moves in the direction just described the track 59 bridges the contacts 99 and 102 whereupon the current flows from the battery to the coil 97 of the switch 88 whereupon the coil will be heated and heat the thermal responsive arm 96. As the arm 96 heats it moves towards the contacts 112 and 113 and the contact bar 114 bridges the contacts 112 and 113 and establishes a circuit from the battery to the motor as previously described thereby actuating the motor to rotate the signal member 42 and the tracks 59 and 60. As the track 59 reaches the end of its travel it disengages from the contacts 99 and 102 thereby breaking the circuit to the coil 97 whereupon the arm 96 begins to cool and move the contact bar 114 out of engagement with the contacts 112 and 113 thereby breaking the circuit to the motor.

60 The thermal responsive arms 89 and 96 are so regulated that they require considerable time to heat sufficiently to cause their associated contacts to be bridged thereby providing an interval of time between the disengagement of one contact bar and its associated contacts and the heating of the thermal arm of the other circuit whereupon the signal device is stationary for a time between the actuations of the switches 87 and 88.

65 In Figs. 9 and 10 I have indicated generally at 120 a further modified form of signal. This signal is adapted to be permanently secured in the desired position and also may serve as a platform for an officer directing traffic.

70 As shown this device comprises a circular body portion 121 having a flat top as indicated at 122 and having parabolically tapered side walls as indicated at 123. The body also includes a recess 124 and an aperture 120 75 in the top wall which communicates with the recess 124 and is adapted to be closed by a member 126, the top surface of which is adapted to lie flush with the top surface 123 of the body portion.

75 On each of the four sides of the body portion I provide a pair of apertures 128 which communicate with the recess 124 and are provided with translucent closures 129. The closures 129 of each pair are of a differ-

ent color such as red and green, and each of the four sets of closures are of the same color arrangement. Behind each of the closures 129 I provide an electric lamp 130 and screen the lamps one from the other as by members 131. This signal device is adapted to be automatically operated and in Fig. 11 I have diagrammatically shown one form of electrical hook up.

10 In Fig. 11 the lamps behind the red translucent closures are indicated at 135 and 135' and the lamps behind the green translucent closures are indicated at 136 and 136'. All the lamps are connected to one side of a source of electricity such as a battery 137 by a wire 138 and a switch 139. All of the red lamps 135 and the green lamps 136 are connected by a wire 140 to a contact track 141 and a companion contact track 142 is connected by a wire 143 to the other side of the battery 137.

All the red lamps 135' and the green lamps 136' are connected by a wire 144 to a contact 145 and a companion contact 146 is connected by a wire 147 to the wire 143. Thus it will be seen that when the oppositely disposed red lamps 135 are lighted the right angularly disposed green lamps 136 will be lighted and when the oppositely disposed red lamps 135' are lighted the right angularly disposed green lamps 136' will be lighted.

For alternately bridging the contacts 141, 142, 145 and 146, I provide a contact bar 148 mounted on a thermal responsive metal arm 149. This arm is adapted to be heated by an electrical resistance coil 150 which is connected at one end by a wire 151 to the wire 144 and at the other end is connected by a wire 152 to a contact 153. The arm 149 is shown as mounted in a support 154 which includes a movable slide 155 which engages the arm 149 and by which the flexibility of the arm 149 may be adjusted.

45 When the arm 149 is cold the contact bar 148 bridges the contacts 145, 146, and 153, whereupon when the switch 139 is closed the current flows from the battery to the contacts 145, 146 and 153, thereby lighting the lamps 135 and 136 and heating the coil 150 and the arm 149. When the arm becomes warm enough it moves towards the tracks 141 and 142 and breaks the circuit between the contacts 145, 146 and 147, thereby extinguishing the lamps 135 and 136 and allowing the coil 150 to cool.

When the contact bar 148 bridges the tracks 141 and 142 the lamps 135' and 136' are lighted and stay lighted until the arm 149 has cooled sufficiently to move the contact bar out of engagement with the tracks 141 and 142 and into engagement with the contacts 145, 146 and 153 whereupon the operation of the signal will be repeated.

Having thus described my invention, I claim:

In a traffic signal device, a signal member including means to indicate traffic "go" when in one position and traffic "stop" when rotated substantially 90° from the first named position, means to rotatably mount said signal, a pair of electrical conductive tracks mounted on said signal member, a reversible motor arranged to drive said signal member, a control switch, said control switch including two sets of contacts and a movably mounted contact bar adapted to bridge said sets of contacts alternately, a source of electrical energy and means whereby when said contact bar bridges one set of contacts current will be conducted from said source to said motor to rotate said signal member and upon rotation of said member and said tracks to a predetermined point the circuit to said motor will be broken and when said contact bar bridges the other of said sets of contacts current will be conducted from said source to said motor through the other of said tracks and operate said motor in the opposite direction until said other track has rotated a predetermined distance whereupon the circuit to said motor will be broken, and means whereby when the circuit through one of said tracks is broken the other of said tracks will be in a position to complete a circuit to said motor when said contact bar bridges the correct set of contacts, automatic means for actuating said signal member when said control switch is in a neutral position, said automatic means including a pair of automatic switches, said switches each including a pair of contacts and a contact bar adapted to bridge said contacts, said contact bars each being mounted on a thermal responsive arm, an electrical resistance coil associated with each of said arms and adapted to heat said arms, means connecting one of said coils to said battery through one of said tracks when said track is in a predetermined position and means connecting the other of said coils to said battery through the other of said tracks when said other track is in a predetermined position, and said tracks when in another predetermined position being adapted to break the circuit to said coils, said tracks when in one predetermined position being adapted to make a circuit to conduct current to said coils to heat said coils and said thermal arms, said arms when heated being adapted to move said contact bars into engagement with their associated contacts and make a circuit to said motor to operate said motor and actuate said signal member, said automatic switches being operable consecutively.

In testimony whereof, I hereunto affix my signature.

VERN M. OSBORN.
